UNITED STATES PATENT OFFICE.

THOMAS E. MARTIN, OF BUFFALO, NEW YORK.

ROCKING GRATE.

No. 833,934.

Specification of Letters Patent.

Patented Oct. 23, 1906.

Application filed October 21, 1904. Serial No. 229,397.

To all whom it may concern:

Be it known that I, THOMAS E. MARTIN, a citizen of the United States of America, and a resident of the city of Buffalo, county of Erie, and State of New York, have invented a certain new and useful Improvement in Rocking Grates, of which the following is a specification.

My invention contemplates an improvement on the construction shown and described in my prior application, Serial No. 87,240, filed December 26, 1901; and the object, generally stated, of my present invention is the provision of an improved and highly-efficient rocking grate; and a special object is to provide improved means for limiting the rocking or oscillating motion of said bar; and it is also an object to provide certain details and features of improvement tending to increase the general efficiency and serviceability of a rocking grate of this particular character.

To the foregoing and other useful ends my invention consists in matters hereinafter set forth and claimed.

In the accompanying drawings, Figure 1 is a plan view of a rocking grate embodying the principles of my invention, only a few of the grate-bars being shown, certain portions being broken away for convenience of illustration. Fig. 2 is a section on line 2 2 in Fig. 1. Fig. 3 is a side view of one of the bars for supporting the bearing-bars. Fig. 4 is a side view of one of the bearing-bars. Fig. 5 is a side elevation of the grate shown in Fig. 1, the masonry or brickwork being removed to show the construction of the grate, one of the elements F being removed. Fig. 6 is a transverse section on line 6 6 in Fig. 1. Fig. 7 is a section on line 7 7 in Fig. 1. Fig. 8 is a view similar to Fig. 7, showing the grate-bars rocked as far as they can go in one direction.

As thus illustrated, my improved rocking grate comprises the supporting-bars A, the transverse bearing-bars B, mounted in place on said supporting-bars, the grate-bars C, the connecting-bars E, the stationary bars or fillers F, and the rock-shaft G. The said supporting-bars can be secured to the sides of the boiler structure in any suitable or desired manner, but are preferably provided with notches a, adapted to receive the ends of the bearing-bars. Said bearing-bars have their upper edges provided with notches b. The bracket-bearing H, preferably located toward the rear of the structure attached to

one of the bearing-bars, is preferably a closed guide or a bearing in which the rock-shaft G is supported. The other end of said rock-shaft can be supported in the front of the boiler structure. Consequently the bracket-guides I, attached to any or all of the bearing-bars between the two ends of the rock-shaft, are open and of the character shown in Fig. 4. Each guide for the rock-shaft, whether open or closed, is preferably provided with slots, such as the slots i. (Shown in Fig. 4.) The attaching-bolts are inserted through these slots, and with such provision the brackets can be adjusted accurately upon the bearing-bars. The connecting-bars E are each formed with openings, and each has attached to it an open bracket e'. These brackets on the connecting-bars, like the brackets on the bearing-bars, are also provided with slots—such, for example, as the slots e². (Shown in Figs. 7 and 8.) Thus the brackets on the connecting-bars can be accurately adjusted, inasmuch as the fastening-bolts extend through the said slots and through the ears e³ on the connecting-bars, as shown in Figs. 7 and 8. The rock-shaft G is provided with crank-arms g, having crank-pins g' adapted to engage the slots or notches in the brackets e'.

As illustrated, each grate-bar C is provided at its ends with knife-edges c, adapted to engage the notches in the bearing-bars. Also with the construction shown each grate-bar is provided with a leg c', adapted to engage one of the openings in the connecting-bar. At this juncture it will be observed that the grate-bars are arranged in three sections and that the members of each section are connected by one of the connecting-bars E. These connecting-bars are supported by providing each bar with ears having a pivotal connection with certain of the legs projecting downwardly from the grate-bars. In Figs. 7 and 8 three grate-bars in each section are shown provided with the pivotal connections e⁴ between their legs and the ears on the connecting-bars. In this way the connecting-bars are supported by the grate-bars, and each connecting-bar is adapted to rock all of the grate-bars in unison. By oscillating the rock-shaft G it is evident that all of the rocking grate-bars will be oscillated or rocked upon their knife-edge bearings. The shaker-brackets e' serve both as a means for communicating motion from the rock-shaft to the connecting-bars

and as a stop device for limiting the motion of the rocking grate-bars. It will be seen that the latter function of the shaker-brackets is due to the fact that the inner faces of the side portions e^5 of each bracket are just far enough apart to alternately engage the rock-shaft when the grate is rocked or shaken. This is clearly shown in Fig. 8, as in this view the grate is shown with the bars rocked as far as they can go in one direction, the inner face of one of the sides e^5 being in contact with the rock-shaft. In this way the size of the gap or opening in the upper portion of each shaker-bracket determines the extent to which the grate can be rocked.

From the foregoing it will be seen that I provide an improved rocking grate of a very efficient and superior character. With the open shaker-brackets of the character shown in Fig. 4 it is evident that the bearing-bars provided with such brackets can be readily lifted out of the grate without disturbing the rock-shaft.

25 What I claim as my invention is—
 1. A grate comprising rocking grate-bars each provided with a depending leg, a connecting-bar movably engaging said legs, a rock-shaft below the grate-bars and extending parallel therewith, a bracket adjustably secured to said connecting-bar and embracing said shaft, said shaft being provided with a crank engaging said bracket, and the inner faces of the bracket being so spaced in relation to the shaft that they are adapted to alternately engage the same to limit the movement of the grate-bars.

2. A grate comprising rocking grate-bars each provided with a depending leg, a connecting-bar movably engaging said legs, a

rock-shaft below the grate-bars and extending parallel therewith, a bracket secured to said connecting-bar and embracing said shaft, said shaft being provided with a crank engaging said bracket, and the inner faces of the bracket being so spaced in relation to the shaft that they are adapted to alternately engage the same to limit the movement of the grate-bars. 45

3. A grate comprising rocking grate-bars each provided with a depending leg, a connecting-bar movably engaging said legs, a rock-shaft below the grate-bars and extending parallel therewith, a bracket secured to said connecting-bar and embracing said shaft, said shaft being provided with means engaging said bracket, and the inner faces of the bracket being so spaced in relation to the shaft that they are adapted to alternately engage the same to limit the movement of the grate-bars. 50 55

4. A grate comprising rocking grate-bars each provided with a depending leg, a connecting-bar movably engaging said legs, a rock-shaft below the grate-bars and extending parallel therewith, a bracket secured to said connecting-bar and embracing said shaft, said shaft being provided with a crank engaging said bracket, and portions of the bracket at each side of the shaft being so spaced in relation thereto that they are adapted to alternately engage the shaft to limit the movement of the grate-bars. 60 65 70

Signed by me at Buffalo, Erie county, New York, this 17th day of September, 1904.

THOMAS E. MARTIN.
